UNITED STATES PATENT OFFICE.

GEORGE H. SHERWOOD, OF DENVER, COLORADO.

SECTIONAL FORM FOR CONCRETE CONSTRUCTION.

965,026.

Specification of Letters Patent. Patented July 19, 1910.

Application filed February 8, 1910. Serial No. 542,693.

To all whom it may concern:

Be it known that I, GEORGE H. SHERWOOD, a citizen of the United States, residing at Denver, in the county of Denver and State 5 of Colorado, have invented a new and useful Sectional Form for Concrete Construction, of which the following is a specification.

This invention relates to a sectional form for use in the construction of concrete buildings and it is more particularly designed 10 as an improvement upon the structure shown and described in an application filed by me on June 29, 1906, said application bearing Serial Number 324,082.

15 In devices of this character such as heretofore devised it has been necessary to utilize a mass of scaffolding and the like for supporting the forms in their proper positions, this scaffolding interfering seriously 20 with the movements of the workmen.

One of the objects of the present invention is to provide a form which can be supported from points above the floor beams, it thus being possible to work downward in 25 the construction of the building and with the space above and below the forms practically clear.

Another object is to provide a device of this character which can be readily set up 30 and quickly taken down, the forms of all the floors in a structure being supported from above at points between the girders.

With these and other objects in view the invention consists in certain novel details 35 of construction and combinations of parts hereinafter more fully described and pointed out in the claims.

In the accompanying drawings the preferred form of the invention has been 40 shown.

In said drawings:—Figure 1 is a view partly in section and partly in elevation of the form and showing the means employed for supporting the same at points between 45 the girders. Fig. 2 is a section on line A—B Fig. 1 and showing the trussed plank. Fig. 3 is a perspective view of a portion of the soffit. Fig. 4 is a detail view of one of the joist supporting cleats used in connection with the soffit.

Referring to the figures by characters of reference 1 designates a supporting plank mounted at its ends upon posts, this plank being arranged longitudinally under one of 55 the girders C of the floor structure and having a truss rod 3 extended longitudinally

thereunder, said truss rod being similar to the one disclosed in my application heretofore referred to. A soffit 4 is located above the plank 1 and has transverse cleats 5 nailed or otherwise secured to the bottom thereof and extending beyond the edges of the soffit, there being blocks 6 upon the end portions of these cleats. Concrete blocks 7 are mounted on the soffit and are interposed between it and the girder C and secured to the soffit adjacent and parallel with its side edges are longitudinally extending cleats 8, having beveled top faces.

A plank, and soffit, are arranged below 70 each of the girders C in the manner set forth and the upper girders of the building constitute supports for a truss frame consisting of upwardly converging rafters or beams 9 and a head strip 10, the said beams 75 and strip being rigidly but detachably connected and the truss frame preferably extending over one of the beams C while resting upon the two beams at opposite sides thereof. A rod 11 extends through and is 80 supported by each of the beams 9 and projects downwardly through the center of the form 12, which, as shown in Fig. 1, is made up of two sections a and b respectively. These two sections are supported at their 85 meeting ends upon a strip 13 which is engaged by the lower portion of the rod 11, that portion of the rod within the form being surrounded by a sleeve 14 of paper or the like. Joists 15 are mounted on the 90 blocks 6 and support those ends of the sections a and b which are adjacent the girders C. The facing boards 16 hanging from those ends of the sections a and b nearest the girders C are designed to rest upon the 95 beveled faces of the cleats 8, the lower edges of these facing boards being correspondingly beveled.

In using the structure herein described, the frame made up of beams 9 and 10 is 100 first set up upon the girders so as to span them and the truss planks 1 are then set up upon the posts 2 with the soffit in position thereon and the blocks 6 between the soffit and the girders. The sectional form is then 105 placed upon the joists 15 and the cleats 8, and are supported at intermediate points by the rods 11 and strips 13. After the floor has been properly molded the blocks 6 can be knocked out and the joists 15 removed, 110 after which, by withdrawing the rods 11, the sections a and b can be readily lowered

out of position, this removal of the sections being facilitated by reason of the fact that the facing boards 16 are beveled where they contact with the cleats 8. The withdrawal 5 of the rods 11 from the forms is facilitated by utilizing the paper sleeves 18 which prevent the concrete from adhering to the rods. Moreover central openings are thus formed within the molded floor and cables or ropes 10 can be extended downwardly through these openings for the purpose of lowering parts of the form and supporting them at lower levels if so desired.

Obviously, if desired, the middle strip 10 15 of the truss frame can be dispensed with and only two upwardly diverging beams 9 employed, said beams being connected at their upper ends and resting at their lower ends upon adjoining girders.

20 By suspending the forms from a truss frame, a large percentage of the scaffolding heretofore necessary, is dispensed with, and the workmen are given more room. Moreover the material used in the building can 25 be more readily handled because the lower portion of the building can be left clear while the upper floors are being constructed.

It is of course to be understood that various changes may be made in the construction and arrangement of the parts without departing from the spirit or sacrificing any 30 of the advantages of the invention as defined in the appended claims.

What is claimed is:—

35 1. A structure of the class described including soffits, supports therefor, transverse cleats secured to the bottom of each soffit and extending beyond the edges thereof, blocks upon the projecting end portions of 40 the cleats, longitudinally extending cleats upon the side edge portions of the soffits and having beveled top faces, joists removably mounted on the blocks, facing boards removably mounted on the beveled faces of the 45 longitudinal cleats, and form sections extending from the facing boards and resting on the joists, said sections meeting at points intermediate the facing boards, and upwardly extending means for supporting the 50 meeting portions of the form sections.

2. A structure of the class described including soffits, transversely extending cleats secured to the bottom faces thereof and extending beyond the side edges of the soffits, blocks upon the projecting end portions of 55 the cleats, beveled longitudinal cleats upon the side edge portions of the soffits, joists

supported by the blocks, facing boards supported by the beveled longitudinal cleats, form sections resting at their outer ends 60 upon the joists, said sections meeting at a point between the joists, a truss frame fixedly supported above the form sections and soffits, and supports extending downwardly from the truss frame and engaging the meeting portions of the form sections. 65

3. A structure of the class described including soffits, transverse cleats secured to the bottom faces of the soffits and projecting beyond the sides thereof, blocks upon the 70 projecting ends of the cleats, longitudinally extending beveled cleats, upon the side portions of the soffits, joists detachably supported by the blocks, facing boards detachably supported by the beveled cleats, form sections supported at their outer ends by the joists and meeting at their inner ends, a supporting strip extending under the meeting end portions of the form sections, an upwardly extending truss frame disposed 75 entirely above the joists and form sections, and means extending downwardly from the truss frames for supporting said supporting strips.

4. A structure of the class described including upwardly converging rafters constituting portions of a truss, soffits, supports for the soffits, form sections interposed between the soffits and supported at their outer ends by said soffits, supporting strips extending under the inner or adjoining ends 85 of the form sections, and means extending downwardly from the upwardly converging rafters for supporting said strips. 90

5. A structure of the class described including a soffit, supports therefor, beveled longitudinally extending cleats upon the soffit, transversely extending cleats connected to the soffit and projecting therebeyond, spacing blocks upon the said cleats, a supporting frame extending above the soffit, rods depending therefrom, a form consisting of sections supported at their meeting ends by the rods and at their opposite ends by said cleats, and joists upon the blocks and 100 supporting the form sections. 105

In testimony that I claim the foregoing as my own, I have hereto affixed my signature in the presence of two witnesses.

GEORGE H. SHERWOOD.
